UNITED STATES PATENT OFFICE.

WEBESTER F. TRAVES AND CHARLES E. TRAVES, OF LOS ANGELES,
CALIFORNIA.

OILER.

SPECIFICATION forming part of Letters Patent No. 402,632, dated May 7, 1889.

Application filed October 4, 1888. Serial No. 287,252. (No model.)

To all whom it may concern:

Be it known that we, WEBESTER FOREMAN TRAVES and CHARLES EDWARD TRAVES, citizens of the United States, residing at Los Angeles, in the county of Los Angeles and State of California, have invented a new and useful Momentum-Actuated Repeating Oiler, of which the following is a specification.

Our invention relates more particularly to oilers for crank-pins and other bearings having a gyratory motion.

The object of our invention is to devise an oiler which will collect the oil after it has once been used in oiling a bearing and will return it to the top of the bearing to be used again, thus using the oil repeatedly with but little waste. We accomplish this by means of the device described herein and illustrated in the accompanying drawings, in which—

Figure 1 is a longitudinal vertical section of the end of a crank-rod on a steam-engine provided with our improvement. Fig. 2 is a detail of the regulating-valve in the feed-cup with the valve open. Fig. 3 is a view of the regulating feed-valve closed. Fig. 4 is a perspective view of the collecting-cup, one side being broken away. Fig. 5 is a plan view of the collecting-cup. Fig. 6 is an enlarged view of the valve. Fig. 7 is a cross-section of the same on line $x-x$. Fig. 8 is a sectional view, showing the opening in the bottom of the bearing in which the crank-pin is seated. Fig. 9 is a cross-section of the lower strap, D, on line y , Fig. 8.

The operation of our invention depends upon the inertia of the oil and the valve and the gyration of the oiler, and the principle of the invention is that if a suitable conduit be properly arranged leading from the collecting-cup at the bottom of the bearing to the feeding-cup at the top of the bearing the inertia of the oil, when properly controlled by a suitable valve, will cause the oil to flow through such conduit from the collecting-cup up into the feed-cup.

Our invention comprises the combination, with a gyratory bearing, such as a crank-pin, crank-rod, and brasses, of a feed oil-cup located above the bearing, a collecting oil-cup

located below the bearing, a feed oil-passage 50 between the feed oil-cup and the bearing, an escape oil-passage between the bearing and the collecting-cup, a cross-partition in the collecting-cup between the escape oil-passage and one end of the collecting-cup; a passage 55 through such partition, a momentum-actuated valve for such passage to allow the oil to flow into the discharge-chamber from the receiving-chamber and prevent its return, and a tube connecting the exterior end of the 60 collecting-cup with the top of the feed oil-cup.

Our invention also comprises other features and details hereinafter more fully set forth.

The oiler shown in the drawings is the most approved form, and is adapted for use on both stationary and locomotive engines; but different valves may be used in place of those shown, and the valve in the feed-cup may be dispensed with without destroying the utility of our invention. We therefore do not wish to be limited by the feed-valve nor the form of the momentum-valve L M N.

The feed-cup A is seated in the top strap, 75 B, in the ordinary manner, and the collecting-cup C is secured to the bottom strap, D, under the crank-pin E. There is a feed oil-passage, F, between the feed-cup and the crank-pin, and an escape oil-passage, G G' W, between 80 the crank-pin and the collecting-cup. The collecting-cup is provided with a cross-partition, H, dividing it into two chambers. The escape oil-passage G opens into one of these chambers, P, which we call the "receiving-chamber," and the returning-tube I opens from the exterior end of the other chamber, Q, which we call the "discharge-chamber," and extends to and opens into the top of the feed oil-cup.

The partition H is provided with a passage, J, therethrough, which is provided with a suitable valve adapted to be opened and closed by the momentum imparted by the gyration of the oiler when the crank is rotated.

The feed oil-cup may be provided with the feed-regulator K or other suitable regulator, if desired; but a regulator is not absolutely

essential to the operation of our invention. The valve employed by us to close the passage through the partition consists of a metal pin, L, approximately equal in diameter to 5 the diameter of the passage, seated in the passage, and provided at one end with a head, M, and having longitudinal grooves N in the body of the pin from the head to the end of the pin to allow the passage of the oil along 10 the pin. A stop, U, located in the path of the pin, prevents it from being thrown out of the passage J.

We provide a filter, O, in the receiving-chamber beneath the escape oil-passage G, so 15 that the oil which falls into the receiving-chamber P will be filtered before it reaches the discharge-chamber. The filter preferably slants from the top of the partition to the floor of the chamber, near the exterior end 20 thereof, and an opening, R, closed by a plug, S, or other suitable means, is provided in the end of the chamber to allow access into the chamber, so that the sediment from the oil may be removed. The collecting-cup is preferably secured to the strap by screws T, so 25 that it can be removed at pleasure.

The partition H is not flush with the top of the walls of the collecting-cup, space being left between the top of the wall and the face 30 of the strap for the upper end of the filter, which is seated beneath the oil-passage, to be clamped between the partition and the strap without opening the joint between the collecting-cup and the strap.

In the drawings the filter is not illustrated 35 in detail, as there is nothing novel in the formation of the screen through which the oil passes. It should be of close enough mesh to intercept the impurities which may mingle 40 with the oil in passing around the pin.

The oil-regulator K is an apex split cone of 45 spring metal, the tendency of the elasticity of which is to spread the points of the divided apex apart. The outer face of the cone is threaded, and a nut, X, is screwed down upon the upper end of the cone to draw the points toward each other, thus closing the split. The regulator is seated in the oil-passage at the bottom of the feed-cup, and is provided with 50 an axial passage, Y, forming an outlet through the base of the cone from the split in the apex thereof.

The means for collecting the oil and conducting it from the bearing to the collecting-cup comprises a space, as G', left between the brasses V V, extending from side to side beneath the bearing to allow the oil to pass from the pin to the bottom strap, a groove or gutter, W, extending almost from side to side of 60 the top of the strap beneath the space G', and sloping downward from each end toward the middle of the gutter, and the central passage, G, opening approximately at the middle of the gutter and extending downward through 65 the bottom strap to the collecting-cup. When the oiler moves in one direction, the oil and the

valve L M N are displaced by their inertia and enter the discharge-chamber. When the oiler moves in the opposite direction, the valve, being heavier than the oil, will seat 70 itself in the passage before the oil can enter the passage and return to the receiving-chamber. Thus at each movement in one direction oil is forced into the discharge-chamber and will be forced up the return-tube I, and 75 passes into the feed-cup.

Now, having described our invention, what we claim as new, and desire to secure by Letters Patent, is—

1. An oiler comprising a feed oil-cup located above the crank-pin, a collecting oil-cup located below the crank-pin, there being a feed oil-passage between the feed oil-cup and the crank-pin and an escape oil-passage between the bearing and the collecting-cup, a 85 cross-partition in the collecting-cup between the escape oil-passage and one end of the collecting-cup, there being a passage through such partition, a momentum-actuated valve for such passage to allow the oil to flow into 90 the discharge-chamber from the receiving-chamber and prevent its return, and a tube connecting the exterior end of the collecting-cup with the top of the feed oil-cup.

2. An oiler comprising a feed oil-cup located above the crank-pin, a collecting oil-cup located below the crank-pin, there being a feed oil-passage between the feed oil-cup and the crank-pin and an escape oil-passage between the bearing and the collecting-cup, a 100 cross-partition in the collecting-cup between the escape oil-passage and one end of the collecting-cup, there being a passage through such partition, the valve-pin provided at one end with a head and having longitudinal 105 grooves in the body of the pin, and a tube connecting the exterior end of the collecting-cup with the top of the feed oil-cup.

3. In an oiler provided with a feed oil-cup and a collecting oil-cup connected by a tube, the combination of the collecting oil-cup set forth, comprising the receiving-chamber, the discharging-chamber, the partition therebetween, the top of which is not flush with the top of the walls of the collecting-cup, the bottom strap provided with an oil-passage there-through, the filter seated below such oil-passage and having its upper end clamped between the partition and the strap, and fastenings to secure the collecting-cup to the strap. 115

4. In an oiler, the combination of the apex split cone of spring metal seated in the oil-passage of the feed-cup, having its outer face threaded and being provided with an axial passage forming an outlet through the base 120 of the cone, and the nut screwed upon the upper end of the cone.

5. In an oiler such as set forth, the means for collecting the oil and conducting it from the bearing to the collecting-cup, comprising the brasses having a space between them extending from side to side beneath the bear- 130

ing to allow the oil to pass from the pin to the bottom strap, a gutter extending almost from side to side of the top of the strap beneath such space and sloping downward from each end toward the middle of the gutter, and the central passage opening approximately at the middle of the gutter and ex-

tending downward through the bottom strap to the collecting-cup.
